UNITED STATES PATENT OFFICE

WALTER L. TAYLOR, OF LOMA LINDA, CALIFORNIA

SHEET-END INDICATOR

Application filed October 22, 1928. Serial No. 314,173.

This invention relates to improvements in a device for indicating when the end of a sheet has been reached, as for instance in a typewriter.

5 Another object is to provide a simple device which may be attached to any standard form of typewriter without altering the construction of the same and one which will perform the above object.

10 A further object is to produce a device which is economical to manufacture and therefore reasonable to install.

15 A still further object is to provide a device which will give an audible signal rather than a visible signal thereby calling the person's attention to the fact that the end of the sheet has been reached irrespective of the sight.

20 Other objects and advantages will be apparent during the course of the following description.

In the accompanying drawings forming a part of this specification and in which like numerals are employed to designate like parts 25 throughout the same,

Figure 1 is a fragmentary detail view taken on the line 1—1 of Figure 2, and showing the typewriter platen in elevation,

Figure 2 is a cross sectional view taken on the line 2—2 of Figure 1.

Figure 3 is a fragmentary detail cross sectional view taken on the line 3—3 of Figure 4; and

Figure 4 is an enlarged fragmentary view 35 showing the slider and paper engaging finger.

Many attempts have been made to devise means whereby the end of a sheet passing 40 through a typewriter would be indicated thereby informing the operator that further typing must cease. These devices have been so attached to the typewriter that the end of the sheet of papers could be viewed by 45 gazing into adjustable mirrors. Should the operator be gazing away from the indicator, it is quite easy to pass the end of the sheet and write upon the platen.

50 Applicant has produced a device entirely different in principle and one which gives an

audible signal when the end of the paper is reached.

In the accompanying drawings wherein for the purpose of illustration is shown a preferred embodiment of my invention, the numeral 5 designates the platen of any standard form of typewriter over which a sheet of paper 6 is adapted to pass so as to be typed thereon. Secured to the frame of the typewriter in any convenient manner is a slider 60 and for the purpose of illustration I have shown a pair of guide bars 7 and 8 which are supported by the frame 9 and serve to slidably support a slider 11. This slider is substantially C-shaped and to one of the arms 65 of the C is attached a bracket 12, having a flexible portion 13. From this bracket a paper engaging arm 14 extends. This arm carries a prong 16 which contacts the roll 5 and is adapted to underlie the edge of the 70 sheet 6. The sides of the prong 16 are rolled as shown at 17 and 18 the purpose of which 75 will be later seen.

A spring 19 is connected to one of the arms of the C and has its opposite end secured to a bracket 21 which is in turn fastened to the rods 7 and 8. The tendency of this spring 19 is to move slider 11 toward the right of the drawing. A setting rod 22 is slidably supported through the frame 9 and extends 80 through the slider 11 and carries a stop 23 adjacent its end portion to which is secured a spring 24 the opposite end of which spring also connects the bracket 21. A handle 26 is secured to the rod 22 thereby enabling the 85 same to be more easily manipulated.

A lever 27 is pivoted to a support 28 carried upon the rods 7 and 8. This lever is connected to a hammer arm 29 having a hammer 31 which is adapted to engage a bell 32. In 90 viewing Figure 2 it will be noted that the device is preferably inserted between the engaging rolls 33 and 34. The rod 35 commonly employed to support certain portions of the typewriting may also be used for supporting the bracket 21.

The manner of operating the device is as follows:

Assuming that the same is attached to a typewriter a sheet of paper is placed within 100

the typewriter in the customary manner. By now moving the rod 22 toward the left, the stop 23 will contact the slider 11 and push the same toward the left of the drawing. This will cause the prong 16 to move off from the paper (that is assuming that the paper has been placed upon the roll so that it will pass beneath the prong 16 due to the flared portions 17 and 18. As soon as the rod 22 is released the spring 24 will return the rod to its normal position while the spring 19 will pull the slider toward the right of the drawing and cause the prong 16 to pass under the sheet thus raising this edge as illustrated in Figures 1 and 2. When the writing operation has advanced far enough it will be apparent that the side of the sheet will pass out of engagement with the slider, after which the spring 19 will move the slider toward the right of the drawing and into contact with the lever 27. This will cause the hammer lever 29 and the hammer 31 to be actuated and brought into engagement with the bell 32 thus giving an audible signal.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In combination with a typewriter having a platen, supporting means positioned adjacent said platen and parallel therewith, a slider movable on said supporting means, a resilient arm carried by said slider, said arm having a prong engaging said platen, resilient means normally moving said slider in one direction, manual means adapted to move said slider against the tension of said resilient means, an audible signal supported on said supporting means and means actuated by said slider for sounding said audible signal in the manner described.

2. In combination with a typewriter having a platen, a support positioned parallel to said platen, a slider movable on said support, an arm carried by said slider and flexibly secured thereto, a prong carried by said arm and normally engaging said platen, a spring secured to said slider at a remote point, the spring tending to move said slider in one direction, means for moving said slider in the opposite direction from said spring and means for causing an audible signal when said slider is released from engagement with a sheet of paper positioned on said platen.

3. In combination with a typewriter having a platen, a pair of supporting rods secured thereto, a slider movable on said rods and in a direction longitudinal to said platen, said slider having an arm carrying a prong

affixed thereto, said prong bearing on said platen at a point between a sheet of paper and said platen, means for moving said slider on said rod manually in one direction and automatically in the opposite direction, and a bell and clapper adapted to be actuated when the end of said sheet is passed.

In testimony whereof I affix my signature.

WALTER L. TAYLOR.
